CONTAINER

Herman W. Block, New York, N. Y.

Application June 17, 1933, Serial No. 676,289

8 Claims. (Cl. 229—15)

This invention relates to containers, and is particularly directed to boxes for cards bearing sample swatches of cloth, and the like articles.

An object of this invention is to provide a box 5 of the character described, having compartments at the opposite ends thereof, which may be selectively opened, said box being constructed to permit articles within said compartments to be viewed from above and removed from the ends 10 of the box.

A further object of this invention is to provide a strong and compact box of the character described, which shall be relatively inexpensive to manufacture, easy to open and close and yet 15 practical and efficient to a high degree.

Other objects of this invention will in part be obvious and in part hereinafter pointed out.

The invention accordingly consists in the features of construction, combinations of elements, 20 and arrangement of parts which will be exemplified in the construction hereinafter described, and of which the scope of application will be indicated in the following claims.

In the accompanying drawing, in which is 25 shown one of the various possible illustrative embodiments of this invention,

Fig. 1 is a perspective view of a box embodying the invention;

Fig. 2 is a view similar to Fig. 1 but with one 30 compartment partially open;

Fig. 3 is a partial, cross-sectional view taken on line 3—3 of Fig. 1;

Fig. 4 is a top plan view of my improved box 35 with both compartments partially open, and parts broken away to show the interior construction; and

Fig. 5 is a side elevational view of my improved box with one compartment open and showing cards within the compartments of said box.

Referring now in detail to the drawing, 10 designates a box or container embodying the invention, here shown to comprise a bottom wall 11 of rectangular shape from the sides of which there extend upwardly a pair of similar, parallel, 15 rectangular side walls 12 and 13. Interconnecting said side walls 12 and 13 and contacting the upper surface of said bottom wall 11, is an up-standing transverse partition 15, preferably of the same height as said side walls. Hinged to 20 the ends of said bottom wall 11, as at 17, are a pair of similar end walls 18, adapted to be swung to vertical position to close the ends of the box. When the end walls are in vertical 25 position the end portions 19 thereof preferably

contact the end edges 20 and 21 of the side walls 12 and 13, respectively.

The walls 11, 12, 15 and 18 of the box may be constructed of cardboard, paper board, wood or any other suitable stiff material, and are preferably covered with canvas or the like flexible sheet material on one or both sides thereof. The flexible covering preferably interconnects the end walls 18 to the bottom wall 11, thus providing the hinge connections 17 for said end walls. 65

The box 10 is thus divided by partition 15 into two compartments. For covering the compartments of said box there is provided a cover member 23 comprising a pair of similar, symmetrically disposed cover portions 24 and a narrow central strip 25 overlying the upper edge 25a of partition 15.

Each of the cover portions 24 covers one of the compartments and comprises a top wall 26 from the sides of which there extend a pair of 75 parallel, similar side walls 28 adapted to receive the upper edge portions of side walls 12 and 13 therebetween. Interconnecting the side walls 28 of each cover portion 24 and extending from the outer end of top wall 26 of said cover portion 80 is an end wall 29 adapted to receive the upper edge portion of the hinged end wall 18 for retaining the same in vertical position.

The walls of said cover 23 and said central strip 25 may likewise be made of cardboard, 85 paper board, wood or the like stiff material covered on one or both sides thereof, by canvas or other suitable flexible material. The flexible covering preferably interconnects said walls 26 with the central strip 25, as shown in Fig. 3 of 90 the drawing.

The strip 25 is disposed between the inner ends of top walls 26 and is provided with portions 32 contacting portions of the outer surfaces of side walls 12 and 13, and disposed between the inner 95 ends of side walls 28 of the cover. Nails 33, or the like fastening devices, driven through said strip 25 and its end portions 32 and side walls 12 and 13 and piercing the top and side end edges of the partition 15, serve to firmly attach 100 the cover to the central portion of said box. The cover portions 24 are thus hinged, as at 27, on opposite sides of said central strip, each cover portion thus being provided with a separate hinge.

It will now be understood that each cover portion 24 may be swung into position overlying and resting on the other cover portion, as illustrated in Fig. 5. When one cover portion is swung open, the adjacent end wall swings down to lie on the 105 table or surface supporting the box. In such 110

position, a stack of cards 35, for example, bearing sample swatches of cloth, or the like articles, within the open compartment, may be viewed from above, and the top cards may be slipped 5 out successively from the open end of the compartment, the box thus serving as a display device.

Although Fig. 5 of the drawing illustrates the box as a container or display device for cards 10 bearing cloth swatches, said box may obviously be used as a receptacle for various other articles.

The canvas or other flexible hinges for the end walls 18 and cover portions 24 may also be replaced by other suitable hinges, such as ordinary metal hinges.

Instead of covering the walls of the box entirely with canvas or the like flexible material, strips of such material may be used to connect the end walls 18 to the bottom wall 11, and to connect walls 26 to the central strip.

20 After the cards 35 of one compartment are displayed and removed, the same may be replaced, the end wall 18 for said compartment swung upwardly and the open cover portion 24 swung into closed position, thereby retaining said end wall 25 in vertical position to close said compartment.

The other cover portion 24 may then be swung open to overlie the closed cover portion, thus permitting the other end wall 18 to fall to horizontal position and expose the articles in the 30 other compartment.

It will thus be seen that there is provided a device in which the several objects of this invention are achieved, and which is well adapted to meet the conditions of practical use.

25 As various possible embodiments might be made of the above invention, and as various changes might be made in the embodiment set forth, it is to be understood that all matter herein set forth or shown in the accompanying drawing 40 is to be interpreted as illustrative and not in a limiting sense.

Having thus described my invention, I claim as new and desire to secure by Letters Patent:

45 1. A box construction including a unitary bottom wall, a pair of side walls, a cover portion, the cover portion including a section bridging the side walls and secured thereto to retain them in box-forming position, a pair of walls at the ends of the bottom and hinged thereto, the end walls being movable into position to close the openings 50 at the ends between the side walls, and other sections of the cover portion being hinged to said bridging section and movable into encompassing engagement with the side and end walls.

55 2. A box construction including a unitary bottom wall, a pair of side walls, a partition wall extending between the side walls, a cover portion, the cover portion including a section bridging the side walls and secured thereto to retain them in box-forming position, a pair of walls at the ends of the bottom and hinged thereto, the end walls being movable into position to close the openings 60 at the ends between the side walls, and other sections of the cover portion being hinged to said bridging section and movable into encompassing engagement with the side and end walls.

70 3. A box construction including a unitary bottom wall, a pair of side walls, a partition wall extending between the side walls, a cover portion, the cover portion including a section disposed

immediately over the partition, the section being secured to the side walls to retain them in box-forming position, a pair of walls at the ends of the bottom and hinged thereto, the end walls being movable into position to close the openings at the ends between the side walls, and other sections of the cover portion being hinged to said first-mentioned section and movable into encompassing engagement with the side and end walls.

80 4. A box construction including a unitary bottom wall, a pair of side walls, a partition wall extending between the side walls, a cover portion, the cover portion including a section disposed

immediately over the partition, the section being secured to the side walls and the partition to retain them in box-forming position, a pair of walls at the ends of the bottom and hinged thereto, the end walls being movable into position to close the openings at the ends between the side walls, and other sections of the cover portion being hinged to said first-mentioned section and movable into encompassing engagement with the side and end walls.

85 5. A box construction including a unitary bottom wall, a pair of side walls, a partition wall

extending between the side walls, a cover portion, the cover portion including a section extending down along the side walls in line with the partition, means extending through the section extension and the side walls to engage the partition

100 for retaining them in box-forming position, a pair of walls at the ends of the bottom and hinged thereto, the end walls being movable into position to close the openings at the ends between the side walls, and other sections of the cover portion being hinged to said first-mentioned section and movable into encompassing engagement with the side and end walls.

105 6. A box comprising a bottom wall, a pair of side walls extending from the opposite edges of

said bottom wall, a transverse partition interconnecting said side walls, a pair of end walls hinged to the outer ends of said bottom wall, and a cover for said box comprising a pair of similar, 110

symmetrically disposed portions, and a strip portion overlying the top edge of said partition and disposed between said cover portions, each cover portion being hinged to said strip portion and

adapted to cover one of said compartments and having means for retaining one of the hinged 115 end walls in upstanding condition, and fastening members for attaching said central strip portion to said partition.

120 7. A box comprising a unitary bottom wall, unitary side walls, end walls hinged to the edges of

said bottom wall, means disposed centrally over said side walls bridging the latter and having downturned portions connected to said side walls, and cover portions hinged to said bridging means

125 and engageable with said hinged end walls.

130 8. A box comprising a unitary bottom wall, unitary side walls, end walls hinged to the edges of

said bottom wall, means disposed centrally over said side walls bridging the latter and having downturned portions connected to said side walls, movable cover portions engageable with said

135 hinged end walls, and means for hingedly securing said cover portions to said bridging means comprising flexible sheet material interconnecting said cover portions and said bridging means.
